(57) **CLAIM**

The ornamental design for a relief valve component, as shown and described.

DESCRIPTION

FIG. 1 is a side perspective view of a relief valve component, according to a first embodiment of our new design; FIG. 2 is a bottom perspective view thereof;

FIG. 3 is a left side view thereof;

FIG. 4 is a right side view thereof;

FIG. 5 is a top plan view thereof;

FIG. 6 is a bottom plan view thereof;

FIG. 7 is a side perspective view of a relief valve component, according to an alternative embodiment of our new design;

FIG. 8 is a bottom perspective view thereof;

FIG. 9 is a left side view thereof;

FIG. 10 is right side view thereof;

FIG. 11 is a top plan view thereof; and,

FIG. 12 is a bottom plan view thereof.

1 Claim, 6 Drawing Sheets
